HENRY B. CLARK, OF ELIZABETH, NEW JERSEY

APPARATUS FOR TREATING LUMBER

Application filed June 2, 1928. Serial No. 282,460.

This invention relates particularly to apparatus for saturating or impregnating lumber or the like with a preservative or a waterproofing composition. Within recent years, it has been discovered that lumber, especially flooring, can be impregnated with a certain liquid composition so as to prevent the lumber from absorbing moisture and thereby obviating the difficulty frequently encountered in boards swelling and shrinkage by absorption of moisture and subsequent drying. However, the methods and apparatus now used for handling and saturating the lumber are laborious, slow, inefficient and expensive; this being the case especially where a certain number of bundles of boards are lifted by a crane, lowered thereby into a tank or vat for a certain period of time, then removed, conveyed away, drained of surplus material, and dried.

One object of my invention is to provide a novel and improved apparatus for saturating or impregnating material such as lumber with a liquid composition whereby the lumber may be continuously passed through the immersion, draining, and drying stages at one place without attention by operators and in large quantities, the untreated lumber being placed in the apparatus at one point, automatically conveyed, successively and in a continuous path through the liquid composition, a draining and drying chamber, and automatically discharged in finished condition at another point.

Other objects are to provide apparatus of the character described including a novel and improved construction, combination and arrangement of immersing tank, conveyor, draining apparatus, and drying mechanism; to provide such apparatus whereby the time of treatment of the lumber in the various stages may be varied, and to obtain other advantages and results as will be brought out by the following description.

Referring to the accompanying drawings, in which corresponding and like parts are designated throughout the several views by the same reference characters.

Figure 1 is a vertical longitudinal section-

al view through apparatus embodying my invention.

Figure 2 is a transverse vertical sectional view taken on the line 2—2 of Figure 1.

Figure 3 is an enlarged fragmentary side elevation of the basket dumping mechanism, and

Figure 4 is a detached perspective view of one of the baskets for supporting the lumber to be treated.

Specifically describing the illustrated embodiment of my invention, the reference character A designates a tank to contain a liquid 1 with which the lumber or the like is to be saturated or impregnated. Above said tank is arranged a draining and drying chamber B through which the lumber is conveyed after it has been immersed in the liquid treating composition.

In accordance with the invention the lumber or the like to be treated is conveyed in a continuous passage through the liquid 1 in the tank A, then through the draining and drying chamber B and is then automatically deposited upon a conveyor which carries the lumber to the storehouse or to the loading platform. To this end, I may utilize an endless chain conveyor comprising two parallel chains 2 each arranged over a plurality of sprockets and supporting between them as by trunnions 3 or the like a plurality of baskets or other suitable receptacles 4 to receive the lumber to be treated. The chains are shown as arranged with a vertical reach 5 passing over sprockets 6, 7, and 8 the lower one of which is arranged adjacent the bottom of the tank A. The chains pass through an opening 9 at the top and adjacent one end of the tank A, and the lumber C to be treated is brought adjacent the conveyor chains by a suitable conveyor D. The conveyor chains are driven in any suitable manner as by a belt and pulley connection 10 with a suitable source of power. The lumber C may be removed from the conveyor D and deposited in the adjacent basket 4 by an operator or otherwise. After the conveyor chains pass over the sprocket 8 they run along parallel to the bottom of the tank and upwardly and in alternating opposite directions over sprock-

ets 11 and 12 and are then carried over a sprocket 13 and downwardly over a sprocket 14 and then upwardly over a sprocket 15 and downwardly over a sprocket 16 and then upwardly over a sprocket 17 and downwardly over a sprocket 18 and then upwardly over a sprocket 19 and downwardly over a sprocket 20 and then upwardly over a sprocket 21 and downwardly over a sprocket 22 and then upwardly over a sprocket 23 and downwardly over a sprocket 24 and then upwardly over a sprocket 25 and downwardly over a sprocket 26 and then upwardly over a sprocket 27 and downwardly over a sprocket 28 and then upwardly over a sprocket 29 and downwardly over a sprocket 30 and then upwardly over a sprocket 31 and downwardly over a sprocket 32 and then upwardly over a sprocket 33 and downwardly over a sprocket 34 and then upwardly over a sprocket 35 and downwardly over a sprocket 36 and then upwardly over a sprocket 37 and downwardly over a sprocket 38 and then upwardly over a sprocket 39 and downwardly over a sprocket 40 and then upwardly over a sprocket 41 and downwardly over a sprocket 42 and then upwardly over a sprocket 43 and downwardly over a sprocket 44 and then upwardly over a sprocket 45 and downwardly over a sprocket 46 and then upwardly over a sprocket 47 and downwardly over a sprocket 48 and then upwardly over a sprocket 49 and downwardly over a sprocket 50 and then upwardly over a sprocket 51 and downwardly over a sprocket 52 and then upwardly over a sprocket 53 and downwardly over a sprocket 54 and then upwardly over a sprocket 55 and downwardly over a sprocket 56 and then upwardly over a sprocket 57 and downwardly over a sprocket 58 and then upwardly over a sprocket 59 and downwardly over a sprocket 60 and then upwardly over a sprocket 61 and downwardly over a sprocket 62 and then upwardly over a sprocket 63 and downwardly over a sprocket 64 and then upwardly over a sprocket 65 and downwardly over a sprocket 66 and then upwardly over a sprocket 67 and downwardly over a sprocket 68 and then upwardly over a sprocket 69 and downwardly over a sprocket 70 and then upwardly over a sprocket 71 and downwardly over a sprocket 72 and then upwardly over a sprocket 73 and downwardly over a sprocket 74 and then upwardly over a sprocket 75 and downwardly over a sprocket 76 and then upwardly over a sprocket 77 and downwardly over a sprocket 78 and then upwardly over a sprocket 79 and downwardly over a sprocket 80 and then upwardly over a sprocket 81 and downwardly over a sprocket 82 and then upwardly over a sprocket 83 and downwardly over a sprocket 84 and then upwardly over a sprocket 85 and downwardly over a sprocket 86 and then upwardly over a sprocket 87 and downwardly over a sprocket 88 and then upwardly over a sprocket 89 and downwardly over a sprocket 90 and then upwardly over a sprocket 91 and downwardly over a sprocket 92 and then upwardly over a sprocket 93 and downwardly over a sprocket 94 and then upwardly over a sprocket 95 and downwardly over a sprocket 96 and then upwardly over a sprocket 97 and downwardly over a sprocket 98 and then upwardly over a sprocket 99 and downwardly over a sprocket 100.

ets 11, 12 and 13, all submerged in the liquid 1. From the sprocket 13 the chains pass upwardly through an opening 14 in the top of the tank and over sprockets 15 arranged at the bottom of the chamber B. The conveyor 5 chains are then arranged in a plurality of superposed substantially horizontal reaches 16 between a plurality of sprockets 17, the uppermost reach 18 passing outwardly through one end of the chamber B at the 10 top, then upwardly around sprockets 19 and horizontally to the sprockets 6. Preferably the various reaches of the conveyor chains are supported by guides 20 projecting inwardly from the sides of the tank A and chamber B, and preferably, to remove the 15 tension strains on the conveyor chains 2, each of the sprockets is driven by trains of gears 21 and 22, and chain and sprocket connections 23 and 24, the power being derived from the connection 10.

Between the reaches of the conveyor chains in the chamber B are disposed drain plates 25 each of which is shaped to direct the liquid 20 falling therein into a drain passage 26 at one side of the chamber B which extends downwardly into the tank A.

A blower fan or the like 27 is connected to force a jet of air into the lower end of the 30 chamber B, which air is conducted by the tortuous passage formed by the drain plates 25 upwardly to the top of the chamber B from which the air is withdrawn through a pipe 28 back to the inlet of the fan 27. Preferably 35 the air is passed over a steam-heated coil 29 whereby the moisture is removed from the air and heat added thereto.

In operation of the apparatus the conveyor 40 chains are constantly moving in the direction indicated by the arrows, and the lumber or the like C to be treated being placed in the respective baskets 4 is first immersed in the liquid 1, the period of immersion depending on the length of the conveyor reaches and 45 the speed of travel of the conveyor chains. When the baskets reach the sprockets 13 they are lifted from the liquid 1 and carried into the draining and drying chamber B wherein the surplus liquid drains from the lumber 50 onto the drain plates 25 and is conducted back to the tank A. At the same time the lumber in the baskets 4 is subjected to the currents of warm air passing through the chamber B between the drain plates 25, said 55 air drying the lumber so that when the baskets reach the top of the chamber and emerge from the outlet opening 30, the lumber is completely dried. The period of drying is 60 of course variable with the speed of movement and length of the conveyor chains.

For the purpose of maintaining the treating liquid at the required temperature, for example, about 140 degrees F. I may utilize steam-heating coils 36 within the tank and 65 below the surface of the liquid, which are

connected in any suitable manner to a supply of steam.

Immediately adjacent the outlet opening 30 a mechanism E is provided for automatically dumping the baskets. This mechanism 70 may be of any suitable construction, but for the purpose of illustration is shown as comprising a sliding hook 31 having a pin and slot connection 32 with a fixed support and normally influenced in the direction opposite to that of the adjacent reach of the conveyor chains by a tension spring 33. Each basket is provided at its top with a lug 34 which is engaged by said hook 31 as the basket passes beneath the hook. Movement 75 of the conveyor chains after the hook engages said lug, causes the basket to be tilted as indicated at 35 in Figure 3 of the drawings which causes the lumber to fall by gravity upon the conveyor F which carries the lumber to a desired point. Further movement 80 of the conveyor chains causes the lug 34 to disengage itself from the hook 31, whereupon the hook is withdrawn to its normal position by the spring 33.

It will be understood that where a certain ratio in speed of travel of the lumber during the immersing, draining and drying stages is desired, separate conveyors may be used for each operation, one conveyor being arranged to deliver the lumber to the next successive conveyor, in a manner similar to that in which the conveyor chains 2 deliver the finished lumber to the conveyor F. Also it is possible to utilize two separate chambers 95 for the draining and drying operations.

It will be understood that my invention may be embodied in apparatus including details of construction widely different from that herein described, without departing 105 from the spirit or scope of the invention, and I do not desire to be understood as limiting myself to the specific details of construction illustrated and described.

Having thus described my invention, what 110 I claim is:

1. Apparatus of the character described comprising a treating tank to contain a treating substance, a draining and drying chamber, and an endless conveyor passing through 115 said treating substance and said draining and drying chamber for moving the lumber to be treated successively through said treating substance and said chamber, and drain plates beneath the reaches of the conveyor 120 to receive and direct the surplus substance back to said tank.

2. Apparatus of the character described comprising a treating tank to contain a treating substance, a draining and drying chamber, and an endless conveyor passing through 125 said treating substance and said draining and drying chamber for moving the lumber to be treated successively through said treating substance and said chamber, and drain plates 130

beneath the reaches of the conveyor to receive and direct the surplus substance back to said tank, said plates and conveyor reaches being arranged to form a tortuous passage for the lumber being treated, and means for forcing circulation of air through said tortuous passage.

5. Apparatus of the character described comprising a treating tank to contain a treating substance, a draining and drying chamber disposed above said tank, an endless conveyor passing through said treating substance and said draining and drying chamber and arranged with a plurality of vertically spaced substantially horizontal reaches for moving the lumber to be treated successively through said treating substance and said chamber, a plurality of drain plates one beneath each reach of the conveyor in said draining and drying chamber and arranged to form a tortuous passage for the lumber to be treated, and a common drain passage for receiving surplus treating substance from all of said drain plates and direct it back to said tank.

10. Apparatus of the character described comprising a treating tank to contain a treating substance, a draining and drying chamber disposed above said tank, a pair of endless and parallel chains passing through said treating substance and said draining and drying chamber and arranged with a plurality of superposed spaced substantially horizontal reaches, and a plurality of receptacles to receive lumber suspended between said endless chains for moving the lumber to be treated successively through said treating substance and said chamber.

15. The apparatus set forth in claim 4 wherein said endless chains include a substantially vertical reach outside of said tank and said drying and draining chamber, and with the addition of a conveyor for conveying lumber to be treated into proximity with said vertical reach so that the lumber may be deposited from said feeding conveyor into said receptacles.

20. The apparatus set forth in claim 4 wherein said receptacles are suspended on horizontal axes to rotate, and means for automatically tipping said receptacles about said axes to discharge the lumber therefrom as said receptacles emerge from the draining and drying chamber.

HENRY B. CLARK.
